UNITED STATES PATENT OFFICE.

NELS A. NORD, OF RED WING, MINNESOTA.

BUILDING BLOCK.

Application filed November 14, 1921. Serial No. 515,018.

To all whom it may concern:

Be it known that I, NELS A. NORD, a citizen of the United States, residing at Red Wing, in the county of Goodhue and State 5 of Minnesota, have invented certain new and useful Improvements in Building Blocks, of which the following is a specification.

This invention relates to new and useful 10 improvements in building blocks, especially adapted for the construction or building of sewer pipes, silos or other circular structures.

One object of my invention is to provide 15 a building block formed at one end with an offset projecting flange adapted to form a socket or union when the blocks are joined together in forming a sewer pipe.

A further object of my invention is to 20 provide means whereby the adjacent edges of the blocks are securely interlocked or coupled together when arranged in place in the construction of a sewer pipe, silo or other circular structure.

25 With the foregoing and other objects in view that will appear as the nature of the invention is better understood, the same consists in the novel features of construction, combination and arrangement of parts illustrated in the drawings and more particularly pointed out in the appended claim.

In the accompanying drawings, which are for illustrative purposes only and are therefore not drawn to scale:—

35 Fig. 1 is a fragmentary elevation of a sewer pipe, constructed or built up from my improved building block.

Fig. 2 is a similar view of a silo or other circular structure.

40 Fig. 3 is a fragmentary end view, showing how the respective blocks of each section are coupled or interlocked together at their adjacent side edges.

Fig. 4 is a vertical longitudinal section, 45 taken on the plane indicated by the dotted line 4—4 of Fig. 3.

Fig. 5 is a detail perspective view of one of the building blocks and Fig. 6 a side elevation of the same.

50 Referring to the drawings for a more particular description of the invention and in which drawings like parts are designed by like reference characters throughout the several views, the numeral 1 represents a sewer pipe and 2 a silo or other circular structure, each composed of a number of sections 3

formed of a plurality of independent blocks 4. Each block 4 is hollow and of arcuate form in cross section, comprising the inner and outer walls 5 and 6, joined together by 60 the laterally spaced longitudinally disposed radial reinforcing webs 7, 8 and 9, respectively, leaving the longitudinal passages 10 therebetween. One end of each block 4 is formed with an offset longitudinally projecting flange 11 which provides a socket or union for the adjoining end of the adjacent section. This feature is especially useful in the building of sewer pipes. (See Figs. 1 and 4.)

70 The side edge of each block adjacent the web 8 is formed with a hollow longitudinally disposed inwardly projecting tongue 12 which extends the full length of the body of the block and is disposed intermediate 75 the inner and outer walls thereof. The inner wall 13 of this tongue 12 has formed on its inner face, entirely throughout its length, a substantially U-shaped recess 14 adapted to receive a corresponding flange 15 formed 80 on the opposite end of the adjacent block.

It will be noted that the webs 9 of the blocks 4 are spaced inwardly from the adjacent side edges thereof and are curved inwardly to form sockets 16 for the tongues 12; also, that the outer faces 17 of the webs 9 are so curved with respect to the convex outer faces 18 of the tongues 12 as to form tapering spaces 19 therebetween, of outwardly increasing width, for the reception 90 of cement or other binding material 20. To provide for a more effectual interlocking engagement between the edges of adjacent blocks of each circular section, the outer walls 21 of the tongues 12 are formed in 95 their outer faces with a plurality of longitudinally disposed inwardly inclined approximately V-shaped grooves 22 which are spaced apart laterally and receive particles of the cement or other binding material, while the opposite edges and outer walls of the blocks are provided with inwardly projecting flanges 23 which seat in the cement or other binding material agent, as shown in Figure 5.

100 The blocks are arranged in place with the socket forming flanges 11 of each circular section receiving the adjoining ends of the adjacent circular section and with the tongues 12 of the respective blocks of each 110 circular section fitting in the corresponding sockets of the adjacent blocks. The blocks

are also preferably laid with the joints broken, that is to say, with the joints of one layer or section alternating with those of the adjacent layer or section, as illustrated in 5 Figures 1 and 2.

From the foregoing description taken in connection with the drawings, it is thought that the construction, operation and advantages of my invention will be readily understood without requiring a more extended explanation.

Having described my invention, what I claim as new and desire to secure by Letters Patent, is:—

15 A building block comprising a body provided at one edge with a tongue portion which is curved along the plane of its axis beyond the adjacent edge face of the body, said tongue portion being provided at one side with a recess and at its opposite side with V-shaped grooves, the body of the block being provided at its opposite edge with a substantially U-shaped socket the mouth of which is of the same transverse

breadth as the transverse breadth of the 25 tongue portion at its base line, the intermediate portion of the socket being of greater transverse breadth than the intermediate and end portions of the tongue, the socket being of greater depth than the 30 length of the tongue, the mouth portion of the socket being provided at one side with an inwardly disposed flange adapted to fit snugly in the recess upon the tongue of an adjacent block, the relative dimensions of 35 the tongue portion and the socket being such that when two of the blocks are placed edge to edge together the tongue portion of one block is completely received in the socket of the other block, with the face surfaces of 40 the adjacent blocks in close contact with each other and sufficient space being left between one side of the tongue portion only and the adjacent surface of the socket to receive and completely enclose a filling of 45 cement.

In testimony whereof I affix my signature.
NELS A. NORD.
